(57) **CLAIM**

The ornamental design for an armless chair, as shown and described.

DESCRIPTION

FIG. 1 is an isometric view of the right side of the armless chair showing the new design;

FIG. 2 is a front view thereof;

FIG. 3 is a slightly reduced rear view thereof;

FIG. 4 is a slightly reduced right side view thereof;

FIG. 5 is a slightly reduced left side view thereof; and

FIG. 6 is a slightly reduced bottom plan view of the armless chair thereof; and,

FIG. 7 is a slightly reduced top plan view.

The structure shown by dotted lines also forms no part of the invention.
